PREFABRICATED BUILDING
CONSTRUCTION

Edwin O. Klemm, Saginaw, Mich.

Application January 12, 1949, Serial No. 70,439

15 Claims. (Cl. 20—2)

1 My present invention consists of a new house or building construction.

The invention deals with the problem of housing shortage today to the extent that a primary aim thereof is to devise a pre-fabricated type of house having special features of advantage. These features include employment of architectural elements which, from the mechanical angle, may be made economically, and quickly assembled into the ultimate dwelling or building. In this connection it is notable that in building details I employ structural parts and assemblies, making use of lumber, largely, and furnishing labor to the usual artisans employed in the building industry, both at the mill and on the dwelling site where the building is to be erected.

Secondly, my new construction deals with the social phase of enabling the user to construct a dwelling of relatively small size, say two or three rooms, and progressively add rooms or extensions to the original structure without in any way requiring the demolishing, or mutilation, of such original structure. Thus the needs of a small family may be met, as well as those of a family increasing in size, or even a very large family, utilizing all the while a basic plan with many variations according therewith, and basic units of pre-built structure always to be available as a part of the pre-planned constructions.

In its third phase my invention has fully in contemplation the importance of dwelling production, especially, that may be brought within the financial reach of largest number of people having ability to buy homes. To this end I have designed all structural details with a view to obtaining mass production, ease of assemblage at the site of erection, sturdiness of construction for long lasting quality, quick annexing of supplemental chamber or room space, economy of space, and convenience in arrangement of rooms, closets, stairways, and divers other structural features.

Exemplifying one of the above matters in more detail, I deal with the feature of additions to the original building structure. Where the floor joist connections are made to the walls of the building, there are provided openings in the wall leading from the joist ends. These openings originally are capped or closed by what may be ornamental cap blocks or members. Adding a room extension only requires removal of these blocks at the wall from which the addition is to extend, to enable introducing the ends of extension joists of the original type, and

then the walls and ceilings or roofs of the extensions may be made from the same type of prefabricated panel and other units as was the original structure.

5 Another feature of my invention resides in having, as a basic unit of my architectural assembly, a special type of prefabricated panel unit, preferably of wood, though metal may be resorted to in its construction. This panel unit enters into the construction of many portions of the building, i. e., walls, partitions, floors, roofs, doors, windows, counters, cabinets, closets, and any load bearing sections of the erection.

10 Still another feature of my invention lies in the frame construction employed, which is conducive to making curved side and roof buildings and buildings having combined curved and straight sides, with additions of more conventional rectangular shapes. The frame structure is susceptible of being structurally self-supporting and independent of the side and roof structure in this respect. This enables a general curved outer building enclosure to be set up either before or after the frame assemblage is complete, all conducive to a flexibility of erection and material handling not heretofore achieved, to my knowledge.

15 Many other features of my invention of less major importance than those above referred to are included in my invention and will be dealt with in the description hereinafter to be read in conjunction with the annexed drawings, and in the latter:

20 Figure 1 is a perspective view showing a typical dwelling incorporating the general features of my invention, the front side of the dwelling being unclosed to enable the frame construction to be seen, the arrangement of the stairway and certain closet space being disclosed in dotted lines.

25 Figure 2 is a view similar to Figure 1, showing how the general original body construction of the dwelling may be combined with extensions thereof, this view also illustrating the removable cap or cover block at certain sides of the modified dwelling construction, which block may be detached in order to receive extension joists in alignment with those of the original structure. Figure 2 is broken away at a corner of the lower extension from the front of the dwelling to show the frame construction in part.

30 Figure 3 is a view somewhat similar to Figure 2 showing how the dwelling of Figure 1 may be extended in the direction of one end as shown

in Figure 1, for the purpose of adding additional room on the second and first floors.

Figure 4 is a detail combined view showing the cover members for the end openings of two joists as when removed and replaced by rest members or arms, a portion of the view also illustrating one of the cover members in place at the left of the rest arms, it being understood that joists may be substituted for the rest arms or resting members shown.

Figure 5 is a perspective view of the facing panel unit employed in my building construction and utilized for building the sides, floors, and roof features of the said construction.

Figure 6 is a detail perspective view of one of the tongue and groove members of the panel unit alone.

Figure 7 is an end view of the member shown in Figure 6.

Figure 8 is a front edge view of the member shown in Figure 6.

Figure 9 is a fragmentary sectional view of the tongue and groove interlocked portions of two of the members such as shown in Figure 6.

Figure 10 is a perspective view showing partially one of the panel units of Figure 6, as when mounted between two joists, dotted lines showing adjacent panel units as associated with said joists and the joists themselves being illustrated in dotted lines, the view bringing out the manner in which the panel unit actually measures or establishes the distances at which the joists are spaced when they are placed in position.

Figure 11 is a horizontal sectional view through a special panel unit of the general class shown in Figure 5 but designed for providing window construction.

Figure 12 is a view in elevation of the panel unit of Figure 11.

Figure 13 is an edge view of the panel unit of Figure 11.

Figure 14 is a modified form of panel unit illustrated in end view, and showing how the unit structure may be modified for providing different arrangements of the individual members thereof for artistic or other reasons.

Figure 15 is a front elevation of the unit shown in Figure 14 and having curved formation at its upper end to conform with the curvature of the end wall of the dwelling as shown in Figure 1.

Figure 16 is a front elevational view of another type of panel similar to that of Figure 15, and designed for the same general purpose as regards fitting the curved end of the dwelling.

Figure 17 is an end view of the unit shown in Figure 16.

Figure 18 is a perspective view giving a general idea of the frame construction of a building structure of my invention.

Figure 19 is a top plan view of one of the unique joist members of my invention showing the end interlocks for same.

Figure 20 is a side elevation of the joist member of Figure 19.

Figure 21 is an end view of the joist member of Figures 19 and 20.

Figure 22 is a fragmentary view illustrating one of the plate members at the upper ends of two column members, one of the latter shown in full lines and one in dotted lines, with the joist members interlocked with the plate member, of which there would be two spaced apart, one of the joists being shown in full lines as much as may be illustrated in full lines, the other joist being illustrated in dotted lines, and one of the

floor panels being shown in position on the joists in dotted lines, illustrating the manner in which the joists may be actually controlled in spacing by means of said panels, the panels, of course being of standard size for such purpose.

Figure 23 is a view showing largely the members shown in Figure 22, fragmentary in illustrating, and bringing out the openings at the top of the column members for receiving heating pipes, water-pipes, and other service connections of a similar nature, this view showing clearly the manner of the interlocking of the end blocks on the joist member with the plates at the top of the column members.

Figure 24 is a view in side elevation of one of the column members alone.

Figure 25 is an edge elevation of the member shown in Figure 24.

Figure 26 is a perspective view, partly broken away and bringing out some details of modified arrangements of the wall construction, partition construction, that may be embodied in the frame and wall features of the dwelling embodying my invention, the view primarily illustrating the flexibility of the construction under actual conditions of use.

Figure 27 is a fragmentary sectional view bringing out more clearly the mounting of certain of the panel units as for a floor or ceiling construction, upon the joist members, with ceiling or other pipes beneath the panel units for obtaining radiant heating or carrying water or the like to various portions of the dwelling. In this view the joists are shown as cut so as to receive upwardly or downwardly curved sealing plates of suitable flexible metal or the like which may be easily placed in position and also easily removed when access is desired to the parts housed between the panel units and said plates, and for cleaning purposes as well.

Figure 28 is a view somewhat similar to Figure 27, showing a somewhat different arrangement of the sealing plates that may be applied to the joists, as compared with those of Figure 27.

Figure 29 is a fragmentary perspective view showing how the panel units of my invention may be embodied in the curved end wall or roof structure of the dwelling, the board members of the units being disposed to face inwardly and provide a finished wall or ceiling structure, as the case may be, and a metal covering being disposed over the panel units at the edges of the stringers thereof.

Figure 30 is a view similar to Figure 29 but showing how the panel units may be placed in positions reversed to those shown in Figure 29, whereby the board members are outermost and provide a weather protective covering or siding as for use in conjunction with the ends of roof portions of the building shown in Figure 1, or the panels, if placed straight in line, may be employed to supply a regular flat roof structure. In the form of Figure 30 the joists between the edges of the panels will be supplied with the felt weather strips and also may be used to carry the eaves troughs if desired, as illustrated in the figure.

Figure 31 is a front view of certain framework of the main body of the building as shown in Figures 1 and 2, certain of the panel units shown, and others omitted. The view brings out the top roof structure and assemblage of the columnar and joist elements more clearly, and also certain other details.

Figure 32 shows a wall of the building from the foundation to the roof, viewing the panel units edgewise thereof, and in a somewhat diagrammatic manner.

Figure 33 is a general perspective view of the frame structure of the building somewhat like Figure 18 but showing certain architectural details absent in Figure 18; also how certain plate members may have ornamental extensions at ends thereof for projection from walls of the building at corners or elsewhere, together with the use of edge finishing strips at the vertical edges of the panel units.

Figure 34 is a diagrammatic elevational view of my building structure when of generally curved or semi-circular form.

Figures 35, 36 and 37 are sectional views taken on the lines 35—35, 36—36 and 37—37, respectively, of Figure 34, bringing out details of the relations of the side or roof shell portions, joist and panel unit assemblies.

Figure 38 is a perspective view of a modified form of panel unit board member, one which is recessed on opposite sides so as to receive stringer connecting members, one to be on each side of the panel unit made of such board members.

To give a general idea of my dwelling type structure, though my invention is not necessarily limited to such because quite adaptable to other classes of buildings, I first refer to Figure 1 of my drawings. In this figure I depict a generally curved end wall structure with partly curved and partly flat roof sections. The shape is semi-circular, generally speaking, in reference to a two story structure.

The space in the house is economized by placing the stairs 1 at one of the four corners and extending up from the first floor to the second floor, by inclining in the direction of the inclination of the curved end wall 2. This view also discloses the frame structure in the enclosure of the dwelling, which frame structure is erected preferably prior to the enclosure being completed by the erection of the various panels that constitute the units of special novelty of my invention and which are used for the outside wall, end wall, partition, floor, and group structures of the completed dwelling unit. Thus, the frame construction may be employed as a scaffolding to a certain extent for facilitating the emplacement of the various members of the end and side walls, and the roof structure of the completed building unit. The general arrangement of the end wall and roof panel units is observable, as well as the column members, floor, ceiling, and joist members, closets, and wall compartments, in Figure 1. For small dwellings the base structure, as an example, may be fourteen feet from side to side and forty feet from end to end, with no posts in the area, allowing space for living room, dinette, kitchen, lavatory, utility room, and stairway at the first floor, and two bedrooms, a bathroom, and closet space on the second floor.

The sizes of dwellings made in accordance with my invention will of course be standardized, and may be similarly increased proportionally for larger dwellings of original construction. Or, with floor space approximately indicated above for standard size, it is contemplated that my dwelling structure may be of course enlarged by making quickly constructable additions in a manner that will more fully be described hereinafter, operations that may be performed easily upon the original completed building structure some-

what in the manner shown in Figures 2 and 3 of my drawings.

Since much of the construction of a building embodying my invention is wrapped up in the provision of a peculiar form of a basic structural panel unit, I shall refer first to the form of this unit which is designed to be embodied in a form of universal application for different purposes in the building construction and this unit is designed to be of sufficient thickness for insulation against weather, and also for sound insulation. Figure 5 of the drawings illustrates a preferred form of the structural panel unit to which I refer same being a load supporting unit and being especially designed to be made, where wood is used, from lumber provided in short lengths to overcome many undesirable characteristics of lumber, such as warping, undue expansion and contraction, etc. By using short lengths of lumber in this panel unit, waste is avoided and thus a saving in construction cost is afforded, not to mention the facility with which smaller pieces of lumber may be handled in assembling panel units. Each panel unit, generally designated at 20 A in Figure 5, is made up of a series of transverse board members 3 providing a flat body section, and which members 3 are connected by parallel stringers 4 that extend generally the entire length of the panel unit. The transverse board members 3 are largely of the construction seen in Figures 6, 7, and 8, and comprise rather short lengths of board near the opposite ends of which, and on one side, are provided the stringer receiving grooves 5 which may be characterized as cut in notches. The notches are importantly used because they afford a saving of time in that they enable self-aligning of the members 3 in assembling them in the panel. Likewise, the notches 5 aid in preventing the panel from sagging, especially when disposed vertically or in partial vertical direction, and likewise the notches are useful in self-spacing the stringers 4 in the assembly operation. Each of the members 3 of the panels A is provided with a tongue 6 on one longitudinal edge, and a groove 7 on the other edge, after the manner of tongue and groove flooring structure of common known type, and for the purpose of preventing infiltration of weather on joining of the pieces 3 into the final panel structure, as well as providing the usual bracing structure intermediate the members 3. At each end thereof, the member 3 is formed with grooves 8, and when the members 3 are assembled, the various grooves 8 are in alignment 30 and form a continuous groove along each of the opposite longitudinal edges of the panel unit structure. The grooves 8 are designed to receive a sealing strip which is disposed to interlock in the adjacent grooves of two panels when the latter are assembled. Figure 10 illustrates a little more clearly the manner of arrangement of said sealing strips which are designated 9 in said view, and which may be made of various types of material having weather resistant characteristics and general sealing advantages. The strip may be of specially coated wood, or may be made of metal, or may be made of composition of weather-resistant nature. In Figure 5 the panel A is seen fully assembled, with the stringers 4 in the notches 5 of the members 3 and the various tongue and groove portions of the members 3 suitably interlocked to afford complete rigidity and weather resistant assemblage, in an obvious manner. This panel unit A is a structural unit 40 having load supporting characteristics, and it is

designed to be made in special standard sizes and to be used for the construction of walls, partitions, floors, doors, roofs, windows, by certain modification, counters or cabinets, and to provide a truss over wider spaces having in view its load-bearing function. The stringers 4 are intended to be spaced apart standard distances, so that when the panel units are utilized somewhat in the manner shown in Figure 10, the units A will enable the joists 10, see Figure 18, or the columns 11, see the same figure, to be properly spaced when placed in position without the necessity for actually measuring the distances along the plate members 12 at the upper ends of the column members 11, as examples of the utility 15 of the units in the above connection.

The members 3 of the panel units A may of course be nailed or attached to the stringers 4 in any suitable manner for rigid connection between said parts. Under some conditions it is within the purview of my invention, in view of the versatility of the use of the panel member or unit A, that this member may be constructed out of metal parts, such as channels having the general conformation of the members 3, and rectangular channels having the conformation of the stringers 4, and assembled by welding or otherwise should it be desired to employ metallic construction for the said basic panel unit.

In Figures 10 and 18 the manner in which the panel unit A spaces apart the joists is quite clearly shown. The longitudinal edges of each of the panel units overlie the joists beyond the points where the stringers 4 are located and extend about half-way across the thickness of the joists so as to abut with the edges of a corresponding panel member laid down for cooperation with two adjacent joists.

Obviously, the panel units A may be made of different lengths and different widths, but always it should be borne in mind that they should be built in standard sizes, sizes that will fit alongside and endwise of one another and sizes that may be especially designed for use in building, say closets, or square compartments, as the case may be.

Necessarily, there are some variations in the shapes of these panel units A, dependent upon the particular function to be performed by said units. The edges of the members or stringers 4 of the panel units may be square, rounded, and in any other ways beautified to suit the environment of the interior or the exterior exposure of the panel, dependent on whether the said members 4 are located inwardly or externally of the dwelling. Obviously, the members 4 constitute reinforcing or beam type of rigidifying structures in any panel assembly.

In Figures 11, 12, and 13 of my drawings I show a panel unit A' designed primarily for window construction purposes. In this construction a series of the members 3 is used at the top of the panel and the corresponding series of such members 3 at the bottom of the panel. In conjunction with these series of members 3, I employ longitudinal members 13 which are longitudinally grooved to receive the stringers 4. The spacing of the members 13 enables one or more glass panes to be used between the same and between the upper and lower series of members 3, said panes being designated 14 as seen in Figure 11 and in Figure 12. The foregoing illustrates how a window may be made in a uniform standard size by employing the general features of my panel structure, it being understood that the outer edges

of the boards or longitudinal members 13 will be grooved as at 13' so that the grooves will form a continuation of the grooves 8 on the edges of the members 3.

In Figures 14 and 15 I illustrate a form of panel made up and designated A'', the same for the purpose of dealing with the problem of the curvature of the end 2 of a dwelling unit like that in Figure 1. The panels of Figures 14 and 15 are largely made just like the panels A, though at the upper portion the panels A'' may have longitudinal members 15 of different lengths and intermediate tongue and groove connected short transverse members 16 in order to provide variation of possible artistic utility in the panel construction. However, the upper end of the entire panel A'' in Figures 14 and 15 is curved and the curvature is predetermined so that it will fit the general curvature of the end or roof portion of the dwelling structure in Figure 1 illustration, so that there is no necessity to do any cutting or sawing of the panels on the job. The idea of the invention is that everything entering into the construction shall largely be prefabricated and that the dwelling structure to be erected shall be economically made by the assembling of the various prefabricated shapes and the units of the invention.

In Figures 16 and 17 I illustrate in end and elevation views another kind of panel unit designated A''' largely made the same as the unit of Figures 15 and 14 but in which the upper curved end of the unit is provided by forming the uppermost transverse board member 3' of substantially tapering formation in order to give the curved general conformation to the upper end of the unit.

I next refer to the frame construction of my proposed dwelling or building, because this construction is of great importance and fundamental to the carrying out of the objectives of my invention. Reference is now made primarily to Figure 18 of the drawings, which involves an assembly of main constructional features of a building that constitutes what I believe is a new mode of erection and structure in the art of building houses. These features are such that they may be duplicated and arranged to suit various designs of complete housing structure involving various numbers of rooms and various types of extension features that may be built upon an original layout or house construction. As seen in Figure 18, the frame construction includes the joists 10 which are provided usually at opposite ends, but at least at one end, with the interlock blocks 16. The said blocks 16 are attached to opposite sides of the joists 10 at the ends thereof, and project some distance beyond the ends, and the blocks are additionally formed with downwardly extending extensions or lugs 17 of somewhat less longitudinal depth than the general structure of the blocks 16. The building frame also includes the uprights or columns 11 previously referred to and which columns at their lower ends are mounted upon blocks 18 resting upon the floor structure below. The joists 10 are made of predetermined standard lengths, and these lengths control the extent of the span or width of the basic structure of the dwelling. In the example given, the joists are preferably fourteen to sixteen feet long, making the basic structure, therefore, fourteen to sixteen feet wide, from front to rear as seen from Figure 1 of the drawings. The formation of the joists 10 is such as to enable the same to be easily lo-

cated and interlocked and kept in alignment with predetermined places in the structure. The blocks 16 are useful in performing the function of making it possible to easily locate and seal the end closures 25 for certain of the outer spaces at the ends of the joists. Figure 18 illustrates clearly the manner in which the plate members 12 are secured to the columns 11 at the outer and inner sides thereof and in Figure 23 it is to be seen that the plates 12 interlock with the extensions or lugs 17 projecting downwardly from the blocks 16 on the joist ends. This interlock of course affords a rigidifying of the connection between the various wall or partition features of the dwelling, the joists 10 virtually constituting interlocking girders. The plate members 12 rest on shoulders 20 provided by indentations in the front and rear edges of the columns 11 which are members similar to studding of common forms of dwellings, except that it is preferred that these columns or column members 11 shall be of somewhat greater weight and sturdiness of construction. The plate members 12 do not enter fully into the notches or indents 20 of the columns 11 but project substantially half the thickness of these members from said indent portions, as seen most clearly in Figure 23. There is a definite purpose for this formation and arrangement of the parts 11 and 12 because as seen in Figure 18, the panel units A are designed to fit between upper and lower horizontal members, the upper members being the plate members 12 and the lower members being horizontal boards 21 at the outer sides and adjacent to the lower ends of the column members 11. This has to do, of course, with the arrangement of the panel units A at the outer sides of the frame and in conjunction with the showing in Figure 23, it might be noted that by reason of the setting, on the inner shoulder of the columns 11, of the inner plate member 12, any suitable inside finishing boards or wall structures may be applied to the inner edges of the columns 11 flush or inset from the inner surface of the inner plate member 12 to thus provide a suitable finish for inner wall formation. The inner plate members 12 are advantageous also in that they may support curtain rails such as designated at 22, and the wall or windows or other portions thereof may be curtainized very readily with appropriate artistic draperies suspended from the rails 22, as may be desired.

The foregoing represents another major phase of advantage of the type of construction that I employ to provide a means to have the house curtainized on the interior and is a contributing reason for the design and combination of the plate members 12 to be used for curtaining purposes. Dealing further with the frame construction as seen in Figure 18, it is to be understood, of course, that the panels A will be mounted at predetermined intervals between the members 12 and 21 and at the outer sides of the columns 11 so that the stringers 4 of the panel units will predetermine the points of location of the columns 11 without necessity for measurement, just as the said panel units A used for the floor structure in Figure 18 are designed to perform the same function in locating of the distance between the joists 10. The predetermined sizes of the panels A as used in the side walls will of course permit of the employment of the window panels of the type shown in Figures 11 and 12 or curved upper end panels of the type shown in Figures 15 and 16, the widths of all these panels being the same

so that they can properly be located dependent upon where they belong in the building structure. Under these conditions it will be apparent that a window may be located at a very suitable place, depending upon the desires of the architect setting up the erection in his plans. In Figure 18 a short form of panel A is seen at the rear of the floor, and this panel unit may be made, just for example, of one-half the area of the main panel units of the floor or ceiling as shown in this figure, the aim being to have the units designed to make for the erection of spaces for use of joist lengths of all standard sizes. The joist lengths at the rear in Figure 18 are of course short joists because they only span about half the distance of that spanned by the joists 10 for making a relatively small rear compartment such as a sun room or the like, as compared with the front compartment made by the joists 10, which might be a living room, or similar part.

The lower ends of the columns 11 are likewise extended or notched to provide the shoulder portions 23. Under these conditions, of course, base plates or boards may be attached to the opposite sides of the lower ends of the column in a manner similar to the mode of attachment of the head plates or members 12, previously referred to, at the upper ends of the columns.

It will be seen that the outer closing board 21 at the base of the columns 11, which are the front columns, will be nailed or secured in position so that it will lie against the front edges of the front columns 11 which are not notched at such edges at the bottom. As respects the columns 11 at the rear outer side of the house, as seen in Figure 18, these also are not notched at their outer lower edges, so that boards like the boards 21 may lie flush against these outer edges of the columns 11 for suitable and rigid attachment thereto. Below the boards or members 21, the lower edges of which are approximately flush with the lower sides of the panels A for the floor at the base of the columns 11, are located closing boards 24 which close the spaces between the adjacent blocks 16 of the joists 10. These members 24 are rather short boards and their ends are spaced apart so that an opening is provided between such ends that leads to the space between the blocks 16 of each of the joists. For closing the space between the said blocks 16 at the outer end of each of the joists 10 where said joist is adjacent to the outer side, in Figure 18 the front side of the building, I use removable cover or cap members 25. The members 25 may be of ornamental shapes. They could be round, or rectangular as illustrated, with bevelled edges, and they may be secured in place quite rigidly by nailing or other attachment to the boards 21 and 24. Whenever an addition to the front of the house is desired to be erected, all that is necessary to do in order to emplace the extension joists in position is to remove the cover members 25 and then the notched out ends 26 of extension joists 27 as seen in dotted lines at the rear of Figure 18 may be introduced into the openings exposed by removal of the members 25 and will form direct longitudinal continuation joists for the extension structure that is to be added to the front of the house as seen in Figure 2.

Under some conditions, referring to Figure 4, it is desirable to use rest members that may be readily disposed in longitudinal alignment with joists. Such rest members are shown in Figure 4 at 27a. These members, instead of joist members, may be introduced into the spacing be-

between the blocks 16 at the ends of the joists 10 when the suitable cover members 25 have been removed, and such rest members may be employed to support balcony extensions of the house for practical utility and also for enhancing the artistic construction of the dwelling, or such rest members, if short, may be employed to support window boxes or the like.

As seen in Figure 23, at the upper ends thereof the column members 11 are provided with transverse openings 28 which may be of different sizes and which are intended to enable pipes or electric lighting conduits or like fixture members to be placed in position after the frame of the building is erected. The various openings 28 are in alignment and thus provide continuous passage ways in the space between the plates 12 and through the upper ends of the column members 11 for such provisions as above indicated, including heating, water, and similar pipes or conduits. It is obvious that the plate members 12 used to support the joists 10 afford a substantial means to finish the appearance of the house inside and outside, as well as carrying the load of the floors, roofs, and similar features of the dwelling construction, depending on the location of the members. The lowermost of the side or plate members 12 (see Figure 18) may be and are used as a part of the foundation space for mounting on conventional cement or brick footing. Obviously it may be envisioned from Figure 18 that the columns 11 may be extended up for second floor construction, or even higher as may be desired, depending upon the size of the dwelling, and the joist arrangement is such that these joists may be extended forwardly and rearwardly to any desired distance for erecting extensions forwardly and rearwardly of the dwelling. Likewise, the dwelling may be added to endwise, after the manner illustrated in Figure 3, by building extensions thereon.

Referring to Figure 26, it will be seen from this figure that the basic panel units may be employed in different ways for facilitating the construction of partitions, walls, closets, rooms like a bathroom as shown at B in this figure, and, under some conditions the stringer members 4 are quite adapted to have doors 29 hinged thereto. Shelf units may be installed as shown at C between panel members or units A of the partition, extending outwardly therefrom, and as shown at E in Figure 26 inset closet spaces may be easily produced.

Figure 26 illustrates clearly how the panel units may be employed in diversified arrangements and for many different purposes.

In Figures 27 and 28 I have illustrated sectional views of ceilings of second floors to show how in Figure 27 various kinds of piping, electric conduits, or air conduits may be channeled between the floor joists. Ceiling lights may be easily installed at the time of erection or after the erection of the house. For improving the appearance of the ceiling wherever needed, flexible materials such as beautiful plywood or metallic decorated surface members may be used by being quickly coved into the space between the joists 10a, said joists being provided with grooves for receiving the edges of the plywood or metal plates designated 30, the said plates may be bellied upwardly or downwardly as shown at the left and right of Figure 26, respectively. They may be quickly installed and they may be readily removed when necessary. A modified form of

arrangement of the decorative ceiling flexible plate members 31 is shown in Figure 28.

In Figure 29 I provide an enlarged sectional view of the roof shown in Figure 1 of my drawings, and it will be observed that the roof panels are the same panel units A previously described, arranged somewhat at an angle to each other and interlocked by means of the strips 9 at the upper and lower longitudinal edges of the said panels. The strips are designed to seal and strengthen the joining of the panels of the edges, maintain the same leak-proof and prevent infiltration of the weather. In this construction the panel units A face inwardly, and when they are made of wood they may afford a very interesting decorative phase of the house construction if the grain of the wood is suitable, or they may be painted, dependent upon the whim and artistic desires of the owner of the dwelling.

On the outside of the stringer members 4 of the panel units I contemplate applying a shell or cover which will be made of sections of plywood immunized to weather conditions by suitable treatment, or the shell may be made of steel, aluminum, or other sheetmetal sections suitably nailed or otherwise secured to the various stringer members 4 of the unit base. Moreover, the above construction affords a double side structure which is a feature of importance in that it provides an intermediate space to resist the penetration of cold and heat under summer and winter weather conditions.

Another form of roof construction which may be employed and still utilize the panel units A is shown in Figure 30. In this view the stringers 4 of the panel units face inwardly and the shell, plywood lining, or metalling inner structure is designated 32 and is attached to the stringer members 4 at their inner edges as contrasted with the disposition of the shell 33 at the outer edges of said stringer members in the construction of Figure 29.

Under the conditions of the construction of Figure 30, the members 3 of the units A are designed to take the weather and will be finished for weather resistance in any suitable manner as by being suitably painted or weather protected in any desirable way. In Figure 30 the manner in which rain troughs 34 may be held in place by having inner end extensions disposed between the adjacent longitudinal edges of the panel members A are fastened in place by nails or otherwise, is disclosed. Of course the space between the panel members A and the angles of the joinder of the longitudinal edges of the same in the construction of Figure 30 may be filled with water and air-resistant material in the operation of rendering the roof weather protected. In some locations of the building structure the space between the panel members are filled with longitudinal strip of wood which will give a proper weather seal and extra strengthening for the joining of the panels. This strip of wood comprises a very important part of the structural elements especially when the panels are used in a vertical position as in Figure 26 and indicated as 9a. This strip, sometimes as occasions require in the design of the rooms and walls, will substitute for the column 11.

Figure 31 shows how the top roof members composed of panel units as seen in Figure 5 are laid on joists 35, 36 and 37 using the interlocking system of blocks 16. This prevents sagging of the panel units. The joists 10 rest on the columnar members 11. The panel units on the

curved ends of the semi-circular body structure are not supported by any joists. The panel units when positioned at an angle of 45 degrees and almost 90 degrees from the nearly flat position shown on top of the structure, act as a truss or become "joists in themselves" and, therefore, are self-supporting. These panel units need but be anchored to the side walls. On the inner surface of these side wall panels are nailed cleats 38. To these cleats are fastened the ends of panel units. The strips 9 strengthen, join and weather seal the panels. Said strips 9 may be rigid, partially rigid, of composition or metal, or both.

The boards 3a of Figure 38 of the drawings are like those 3 previously described except that they are each formed with one stringer recess on each side so the stringers 4 do not lie on the same side as those of the panel unit in Figure 5, for example, and other figures of the drawings. The utility of panel units made of the boards 3a will be seen in Figure 26 of the drawings.

Figures 35, 36 and 37 bring out clearly the roof panel unit mountings upon the joists, and the relation of the shell, or plyboard or metal covering, to the panel units adjacent thereto.

Having thus described my invention, what I claim as new and desire to secure by Letters Patent of the United States, is:

1. A building construction comprising a framework including a series of column members spaced apart and disposed in alignment, a second series of column members spaced apart and disposed in alignment, plate members fastened to the column members of each series at corresponding ends thereof and to opposite edges of the column members, and wood joist members of prefabricated form having attached preformed end parts extending therefrom on opposite sides thereof interlocking between the plate members of the two series of column members, said interlocking parts comprising wood blocks attached at opposite sides of the ends of the joist members and having downward projections engaging between the adjacent plate members.

2. A building construction as claimed in claim 1, combined with panel units supported on opposite edge portions on the joist members and each panel unit comprising a body having spaced stringers spaced from the adjacent edges of the panel unit and projecting from one side thereof and engaging between and against adjacent joists for predetermining the spacing of the latter, said stringers resting on the joist interlocking parts aforesaid.

3. A building construction as claimed in claim 1, combined with panel units arranged so as to be supported on the joist members and each panel unit comprising a body having spaced stringers projecting from one side thereof and engaging between and against adjacent joists for predetermining the spacing of the latter, and other panel units of the same width and construction as those first mentioned arranged at one side of the column members and attached thereto and having spaced stringer members lying between and against adjacent column members for predetermining the spacing of the latter.

4. A building construction as claimed in claim 1, combined with panel members attached to the outer sides of the column members for forming a wall, there being wall openings in alignment with the ends of the joist members, and a removable cover member for said openings detachable for enabling other aligned joist members to be

engaged with the plate members first mentioned.

5. A building construction comprising spaced column members, plate members attached to the column members at the upper and lower ends thereof and at corresponding outer sides thereof, vertical panel units comprising each a body and spaced stringers attached to the body at the inner side thereof slightly spaced from the vertical edges of the body, and arranged to lie against the opposing adjacent sides of spaced column members with said vertical edges overlapping the outer edges of adjacent column members, for predetermining the spacing and reinforcing of the latter, said panel units being supported on and fastened to the column members and lying between the plate members at the upper and lower ends of the column members.

6. A building construction comprising a framework and a covering outer wall for forming side and roof sections of the construction, said covering wall including a series of panel units, each panel unit comprising transverse boards and longitudinal stringers applied to the boards at one side and secured thereto in spaced relation, adjacent panel units having grooves at the end edges of said transverse boards and having such edges juxtaposed in abutting relation, and sealing means in said grooves between the juxtaposed edges of the panel units, the sealing means interlocking the juxtaposed edges of the panel units, combined with a covering applied to the free edges of the stringers in spaced relation to the bodies of the panel units.

7. In a building construction, a frame-work comprising a plurality of column members, spaced apart for carrying vertical loads, horizontal plate members attached to the outer and inner edges of the column members, joists comprising unitary prefabricated end blocks interlocking between the plate members and supported by said blocks on the column members, and panel members comprising body portions having spaced stringers unitary therewith and disposed to lie between and flat against adjacent sides of said joists and supported at their ends on the said blocks and thereby on said plates to carry vertical loads.

8. In a building construction, a frame-work comprising a series of spaced column members, a second series of spaced column members spaced from the first series, a horizontal plate member carried by each of the series of column members, joists extending from one series of column members to the second series of such members, said joists having end interlocking members fabricated in unit therewith and resting on and interlocking with the plate members of the two series of column members to predetermine the spacing of the said series, and panel members each comprising a body unit having spaced stringers parallel with and engaging adjacent sides of a pair of joists to predetermine spacing of the latter and reinforcing said joists, said stringers of each panel resting on the said interlocking members and thus carried by the plate members of the two series of column members.

9. A building construction as claimed in claim 8, in which the unitary end interlocking members of the joists consist of blocks attached to opposite sides of each joist end, said blocks having lugs extending downwardly to engage the plate members, and each block extending from the adjacent side of the joist member to form a rest for an adjacent stringer of the panel member above same, edge portions of each panel member

outwardly of the stringers being seated on the adjacent top portions of spaced joists.

10. A building construction as claimed in claim 7, in which the stringers of each panel member are of a continuous length corresponding to that of an adjacent joist.

11. In a building construction, a frame-work comprising spaced series of column members arranged in spaced relation, a plate member connecting the column members of each series, a series of joists spanning the space between the two series of column members, each joist resting at its ends on the said plate members, wall members on the outer side of each series of column members formed with openings opposite each joist end for receiving another joist end of an extension addition to said frame-work, and cap members closing said openings and removably mounted on the frame-work so as to permit, when removed, the introduction through each opening of the end of an extension joist.

12. A building construction as claimed in claim 11, in which each joist comprises a body having spaced blocks at each end formed with downwardly extending spaced parts, to engage the plate members, and with endwise extending spaced parts, to receive the end of the body of an extension joist when a cap member at the end of a joist is removed.

13. In a building construction, in combination, a framework comprising a plurality of spaced series of column members, a horizontal upper plate member connecting the top portions of the column members of each series, spaced apart joists supported at opposite ends on the plate members of the spaced series of column members, each joist having a pair of side interlock blocks at opposite sides of each end to engage down over the plate member adjacent such end to interlock the plate members together, and a prefabricated panel unit spanning the space between said joists and having spaced longitudinal stringers on its underside parallel with and adjacent to the adjacent sides of the spaced joists, each stringer being spaced slightly from the adjacent longitudinal edge of the panel unit and which edge rests on the top of the adjacent joist, and each of said stringers resting at the ends thereof on the interlock blocks on the opposite ends of an adjacent joist.

14. In a building construction, in combination, a framework comprising a plurality of spaced series of column members, a horizontal upper plate member connecting the top portions of the column members of each series, spaced apart joists supported at opposite ends on the plate members of the spaced series of column members, each joist having a pair of side interlock blocks at opposite sides of each end to engage down over the plate member adjacent such end to interlock the plate members together, and a prefabricated

panel unit spanning the space between said joists and having spaced longitudinal stringers on its underside parallel with and adjacent to the adjacent sides of the spaced joists, each stringer being spaced slightly from the adjacent longitudinal edge of the panel unit and which edge rests on the top of the adjacent joist, and each of said stringers resting at the ends thereof on the interlock blocks on the opposite ends of an adjacent joist, the column members and the said joists being equidistantly spaced apart, wall panel members of like construction to those above described emplaced between the column members with the stringers thereof alongside and against the adjacent sides of the column members, a lower horizontal plate member connecting the lower ends of the column members, the said wall panel members being disposed between the upper and lower plate members.

15. A building construction as claimed in claim 13, in which the panel units are made up of a series of board members laid edge to edge transverse and permanently secured to the stringers, said board members having aligned notched portions near their ends receiving the said stringers and interlocking the latter to the board members.
